WATER COOLER

Russell J. Lukey, 3925 U St., Sacramento, Calif.

Filed Mar. 22, 1960, Ser. No. 59,836

Term of patent 14 years

(Cl. D67—4)

FIG. 2

FIG. 3

FIG. 1

FIG. 4

Figure 1 is a front elevational view of a water cooler, showing my new design;

The side not shown is the same as the side shown and the rear is substantially the same as the front except for the dispensing element.

I claim:

The ornamental design for a water cooler, as shown and described.
